UNITED STATES PATENT OFFICE.

JOSEPH JAY, GUSTAVE JALLIFFIER, AND AUGUSTIN BLANC, OF GRENOBLE, FRANCE.

DESIGN FOR A PROFILED STRUCTURAL METAL BEAM.

42,537.

Specification for Design.

Patented May 21, 1912.

Application filed April 26, 1910. Serial No. 557,835. Term of patent 7 years.

To all whom it may concern:

Be it known that we, JOSEPH JAY, GUSTAVE JALLIFFIER, and AUGUSTIN BLANC, citizens of the French Republic, residing at Grenoble, Isère, in France, have invented a new, original, and ornamental Design for Profiled Structural Metal Beams, of which the following is a specification, reference being had to the accompanying drawing, forming part thereof.

Figure 1, is a perspective view of the design. Fig. 2, is a bottom plan view.

We claim:

The ornamental design for a profiled structural metal beam as shown.

J. JAY.
G. JALLIFFIER.
AUG. BLANC.
